UNITED STATES PATENT OFFICE.

MAX. C. SHULER, OF CHARLOTTE, AND EDWIN H. SHULER, OF LANSING, MICHIGAN.

GAS-BURNER.

1,376,836.

Specification of Letters Patent. Patented May 3, 1921.

Application filed October 10, 1919. Serial No. 329,758.

To all whom it may concern:

Be it known that we, MAX. C. SHULER and EDWIN H. SHULER, citizens of the United States, residing at Charlotte, county of 5 Eaton, State of Michigan, and Lansing, county of Ingham, State of Michigan, respectively, have invented certain new and useful Improvements in Gas-Burners, of which the following is a specification.

10 This invention relates to improvements in gas burners.

The main objects of this invention are:

First, to provide an improved gas burner having a pilot, in which the gas is automatically turned on when an object is placed 15 upon the grid above the burner.

Second, to provide an improved gas burner having these advantages which may be embodied in burners to be substituted as 20 a unit for burners now commonly used in gas stoves, gas plates and the like.

Third, to provide an improved gas burner having these advantages which is economical in structure, and one which is not likely 25 to get out of repair in use.

Further objects, and objects relating to structural details will definitely appear from the detailed description to follow.

We accomplish the objects of our invention 30 by the devices and means described in the following specification. The invention is clearly defined and pointed out in the claims.

A structure which is a preferred embodiment 35 of our invention is clearly illustrated in the accompanying drawing forming a part of this specification, in which—

Figure I is a plan view of a gas burner embodying the features of my invention, a 40 portion of a stove top or grid being broken away as is also the gas supply pipe.

Fig. II is a detail view partially in vertical section on a line corresponding to line 2—2 of Figs. I, IV, V and VI, the parts 45 being shown in their normal position or with the main burner valve closed.

Fig. III is a detail vertical section corresponding to Fig. II, with a cooking utensil shown on the grid, and the parts in their 50 operated position or with the main burner valve open.

Fig. IV is a detail vertical section on a line corresponding to line 4—4 of Figs. II and V, showing structural details.

55 Fig. V is a plan view of the burner head

on a line corresponding to line 5—5 of Fig. IV, the operating member being sectioned.

Fig. VI is a detail horizontal section on a line corresponding to the broken line 6—6 of Fig. II.

In the drawing similar reference characters refer to similar parts throughout the several views, and the sectional views are taken looking in the direction of the little arrows at the ends of the section lines.

Referring to the drawings, 1 represents the frame of a gas stove or gas plate and 2 the grid or top thereof adapted to receive the article to be heated such as a cooking utensil 3, shown conventionally in Fig. III. 70 The main gas burner comprises the head 4 having radiating arms 5, the head and arms being provided with a plurality of jet orifices. The burner has a Bunsen tube 6 adapted to receive gas from the supply nozzle 7 on the gas supply pipe 8. The tube 6 has air openings 9 controlled by the shutter 10 having air openings 11 therein.

The pilot burner 12 is mounted on the gas supply tube 13, the pilot burner being 80 disposed centrally of the main burner. The tube 13 is mounted for longitudinal reciprocating movement within the Bunsen tube 6, the outer end of the supply tube being supported by the bridge or spider 14 at its 85 outer end and being arranged through the walls of the burner as clearly shown in Figs. II and III. The nozzle has a conical valve seat 15 while the member 13 is provided with a conical valve 16 coacting with 90 this seat to control the delivery of gas to the main burner. The member 13 has an opening 17 therein aligned with the opening of the nozzle to receive gas therefrom when the valve is open and also when closed, thus 95 maintaining a constant flame at the pilot.

A spring 18 is arranged on the member 13 to urge the valve to its seat, one end of the spring being seated against the wall of the burner and the other engaging a pin 19 on 100 the tube.

A valve actuating member 20 is disposed vertically through an opening 21 in the ear on the grid, the actuating member is actuating member is provided with a head 23 105 which normally projects above the surface of the grid so that when an object is placed on the grid, the actuating member is actuated to open the main burner valve. To accomplish this, the actuating member is 110

provided with a cam 24 coacting with pins 25 on the member 13, so that when the actuating member is depressed, the member 13 is carried back to open the valve. The 5 lower end of the actuating member is bifurcated to embrace the member 13, thus securing a balancing of parts. The actuating member also carries supporting pins 26 embracing the pilot burner holding it in up- 10 right position, but permitting its lateral movement as the member 13 is shifted.

When an object is removed from the grid, the actuating member is returned to its initial position by means of the weight 27 15 pivoted at 28 on the hangers 29 depending from the burner body, the weight having an arm 30 engaging the lower end of the member 20 as shown. As the member 20 is returned the spring 18 seats the valve and 20 cuts off the main burner.

With this arrangement of parts, the opening and closing of the main burner is entirely automatic, and as a constant supply of gas is provided for the pilot, the main burner is 25 automatically lighted when an object is placed upon the grid.

Our improved gas burner is well adapted to be substituted for burners now commonly in use. We have not attempted to illustrate 30 or describe other modifications and structural details which might be necessary or desirable to adapt our improvements to different stove or gas plate structures, as we believe the disclosure made will enable those 35 skilled in the art to which this invention relates to make such modifications or adaptations as required.

Having thus described our invention, what we claim as new and desire to secure 40 by Letters Patent is:

1. In a structure of the class described, the combination of a grid, a main burner disposed below said grid and provided with a Bunsen tube and a nozzle delivering thereto and having a valve seat at its inner end, a pilot burner operatively associated with said main burner, a pilot burner supply tube carrying said pilot burner and mounted to reciprocate longitudinally in said Bunsen 45 tube and having a valve at its outer end coacting with said valve seat in said nozzle to control the delivery of gas to the main burner and an inlet opening registering with the nozzle opening when said valve is closed permitting the passage of gas to the pilot burner, a valve actuating member mounted on said burner to reciprocate vertically and adapted to be actuated by an object placed on said grid, and a coiled spring arranged 50 on said pilot supply tube to urge said valve to its seat, and a weight pivotally mounted on said burner for returning said actuating member to its initial position.

2. In a structure of the class described, 55 the combination of a grid, a main burner

disposed below said grid and provided with a Bunsen tube and a nozzle delivering thereto and having a valve seat at its inner end, a pilot burner operatively associated with said main burner, a pilot burner supply tube carrying said pilot burner and mounted to reciprocate longitudinally in said Bunsen tube and having a valve at its outer end coacting with said valve seat in said nozzle to control the delivery of gas to the main 75 burner and an inlet opening registering with the nozzle opening when said valve is closed permitting the passage of gas to the pilot burner, and a valve actuating member mounted on said burner to reciprocate vertically and adapted to be actuated by an object placed on said grid.

3. In a structure of the class described, the combination of a grid, a main burner disposed below said grid and provided with a Bunsen tube and a nozzle delivering thereto and having a valve seat at its inner end, a pilot burner operatively associated with said main burner, a pilot burner supply tube carrying said pilot burner and mounted to reciprocate longitudinally in said Bunsen tube and having a valve at its outer end coacting with said valve seat in said nozzle to control the delivery of gas to the main burner and an inlet opening registering with the nozzle opening when said valve is closed permitting the passage of gas to the pilot burner, and a valve actuating member mounted on said burner to reciprocate vertically and adapted to be actuated by an object placed on said grid and having supporting pins projecting 90 at the sides of the pilot burner, the lower end of said actuating member being bifurcated to embrace said supply tube and having a cam coacting with laterally projecting pins on said tube to open the valve.

4. In a structure of the class described, the combination of a grid, a main burner, a gas supply nozzle having a valve seat at its inner end, a pilot burner operatively associated with said main burner, a pilot burner supply tube mounted to reciprocate longitudinally and having a valve at its outer end and coacting with said valve seat in said nozzle to control the delivery of gas to the main burner and an inlet opening communicating with the nozzle opening when said valve is closed permitting the passage of gas to the pilot burner, a valve actuating member mounted to reciprocate vertically and adapted to be actuated by an object placed on said grid and having a cam acting on said supply tube to open the valve, a spring arranged to urge said valve to its seat, and a weight pivotally mounted on said burner for returning said actuating member to its initial position.

5. In a structure of the class described, the combination of a grid, a main burner, a gas supply nozzle having a valve seat at its inner 130

end, a pilot burner operatively associated with said main burner, a pilot burner supply tube mounted to reciprocate longitudinally and having a valve at its outer end coacting with said valve seat in said nozzle to control the delivery of gas to the main burner and an inlet opening communicating with the nozzle opening when said valve is closed permitting the passage of gas to the pilot

burner, and a valve actuating member 10 mounted to reciprocate vertically and adapted to be actuated by an object placed on said grid and having a cam acting on said supply tube to open the valve.

In witness whereof, we have hereunto set 15 our hands.

MAX. C. SHULER.
EDWIN H. SHULER.
